[57] CLAIM

The ornamental design for spout, as shown and described.

DESCRIPTION

FIG. 1 is a perspective view taken from the top, front and left side of a spout showing my new design; FIG. 2 is a right side elevational view thereof, the left side being a mirror image of the right side shown; FIG. 3 is a front elevational view thereof; FIG. 4 is a rear elevational view thereof; FIG. 5 is a top view thereof; and FIG. 6 is a bottom view thereof. The fragmentary broken line representation of water and a sink in FIG. 1 is for purposes of illustration only and forms no part of the claimed design.

FIG. 1.

FIG. 2.

FIG. 3.

FIG. 4.

FIG. 5.

FIG. 6.
